S. L. HANSON

TRIP HEAD AND ROPE ATTACHMENT FOR HAY CARRIERS

Filed Dec. 17, 1925

INVENTOR.
SAMUEL L. HANSON.
BY HIS ATTORNEYS.

William Reif & William

UNITED STATES PATENT OFFICE.

SAMUEL L. HANSON, OF ALBERT LEA, MINNESOTA.

TRIP HEAD AND ROPE ATTACHMENT FOR HAY CARRIERS.

Application filed December 17, 1925. Serial No. 75,977.

This invention refers to a device carried by a rope and adapted to be attached thereto or to a rope supported device, and while the invention may be variously applied, it is particularly designed for use in a rope-supported device, such as used in a hay carrier. Such a hay carrier is disclosed in the prior patent to Gustav A. Olson, No. 806,829, granted December 12, 1905, in which a sling pulley is shown supported on the end of a rope.

It is an object of this invention to provide a novel form of rope supported means having a sling pulley supporting device carried thereby.

It is a further object of the invention to provide a rope supported and clamping means comprising separable members into one of which the rope enters centrally and has its separate strands clamped against the same by the other member.

It is more specifically an object of the invention to provide a rope supported means comprising a shell into which the rope centrally enters, said shell having means therein with a plurality of apertures through which the separated strands of the rope pass, a second member being provided adapted to clamp said strands and having means for drawing it and holding it into such clamping relation.

These and other objects and advantages of the invention will be fully set forth in the following description made in connection with the accompanying drawings in which like reference characters refer to like parts through the several views, and in which,

Fig. 1 is a view in side elevation of the device embodying the invention;

Fig. 2 is a vertical section taken on the line 2—2 of Fig. 1, as indicated by the arrows;

Fig. 3 is a horizontal section taken on the line 3—3 of Fig. 2, as indicated by the arrows;

Fig. 4 is a view in side elevation of one of the rope supported and clamping members;

Fig. 5 is a bottom plan view of the device shown in Fig. 4;

Fig. 6 is a vertical section taken on the line 6—6 of Fig. 3, as indicated by the arrows;

Fig. 7 is a view in side elevation of an-

other rope supported clamping member; and

Fig. 8 is a top plan view of the member shown in Fig. 7.

Referring to the drawings, a rope 10 is shown, such as may be used with a hay carrier, such as illustrated in the prior patent, supra. The rope 10 adjacent its end, passes centrally into the top of a shell or member 11 which is illustrated as of substantially cylindrical form and which has a flange or web 11^a intermediate its ends and on its interior having therein or forming with the wall of said shell a plurality of vertically extending openings 11^b. The wall of the shell 11 is cut away to form a plurality of circumferentially extending notches or slots 11^c and the portions of said wall between said slots are tapered somewhat toward their lower end. The flange 11^a has a central aperture 11^d extending therethrough, of angular shape in cross section, illustrated as square. Adapted to co-operate with the member 11 is a cap member 12 illustrated as substantially triangular in form with rounded corners and having a web or flange 12^a at one end, which end is disposed downwardly in normal operation and has a central aperture 12^b. The member 12 has tangs or arms 12^c projecting from the corners thereof which are tapered somewhat in thickness toward their outer ends.

A headed and nutted bolt 13 extends through the apertures 11^d and 12^b and has its nut below member 12. The bolt 13 is illustrated as square in cross section adjacent its head, which square portion is received in the aperture 11^d and kept from turning therein. The head 13^a of bolt 13, as shown in the dotted lines in Fig. 3, is substantially triangular in form with rounded corners so that the head does not obstruct the apertures 11^b.

The rope 10 extends centrally into the upper part of member 11 above flange 11^a and has its strands separated to pass respectively through the openings 11^b. Below flange 11^a, each strand 10^a is carried laterally across said flange and out through the slot 11^c adjacent the opening 11^a through which it passes, as shown in Fig. 3. The bolt 13 is placed in position before the rope is disposed in member 11, as above described. When the strands have been disposed, as above set forth, the member 12

is placed on the bolt 13, said bolt passed through aperture 12^b and the nut applied to said bolt and turned. The member 12 is thus drawn up toward the member 11. The 5 tangs or prongs 12^c, respectively, enter the slots 11^c. Owing to the taper at the bottom of member 11, the member 12 can enter partly therein. When said member 12 is drawn up tightly into position, the strands 10^a are tightly clamped between the web 12^a and the flange 11^a. The strands 10^a are additionally clamped between the ends 10 15 of the prongs 12^c and the bottom of notches 11^c, the parts assuming the position shown in Fig. 2. The device thus has the inner clamping means including the web 11^a and the outer clamping means including the prongs 12^c. When member 12 has been tightened as much as possible against the 20 strands of the rope, said strands are cut off with a sharp knife flush with the outer wall of member 11. The prongs 12^c entering the notches 11^c prevent any rotative movement of cap 12 relative to shell 9.

25 The members 11 and 12 now being firmly clamped on and supported by rope 10, the rope can be drawn upwardly through a sleeve member 14. The member 14 has an upper smaller portion 14^a and a lower larger portion 14^b, thus forming a shoulder 14^c therebetween. The member 11 has a flat top surface which engages with shoulder 14^c so that sleeve 14 is swively carried on the member 11. The sleeve 14 is forked at its 30 lower end and adapted to receive a headed and nutted bolt 15 which carries a yoke 16 with which the sides of a sling pulley member are adapted to co-operate and be connected, as illustrated in the prior patent, 35 supra. The sleeve 14 swivels freely on the member 11 and it may be mentioned that said sleeve has spaced flanges 14^d extending circumferentially thereabout provided for certain functions in the operation of a locking device forming part of the hay carrier. 40

45 From the above description it is seen that applicant has provided a novel, simple and efficient rope supported and clamping means or rope attachment and one on which the sleeve which supports the sling pulley can readily turn. The rope is very effectively clamped and there is no chance of the rope pulling out of the members 11 and 12. The device is extremely simple and a great improvement over the prior art. The device 50 has been amplv demonstrated in actual practice and found to be very successful and efficient.

55 It will, of course, be understood that various changes may be made in the form, details, arrangement and proportions of the parts without departing from the scope of applicant's invention, which, generally stated, consists in a device capable of carrying out the objects above set forth, in the 60 65

novel parts and combinations of parts disclosed and defined in the appended claims.

What is claimed is:

1. A rope supported means having in combination, a shell having an interior flange and openings therethrough for respectively receiving the strands of a rope, a cap co-operating with said shell adapted to clamp said strands against said flange and having means interfitting with said shell to prevent rotation relative thereto, said shell and cap having alining central apertures and a clamping bolt passing through said apertures for drawing and holding said shell and cap together. 70 75 80

2. A rope supported means having in combination, a shell having interior means against which the strands of a rope are adapted to be clamped, and having spaced notches disposed outward of said means through which said strands pass, a member co-operating with said shell to clamp said strands against said means and also having means adapted to enter said notches to clamp said strands therein and prevent relative 90 rotation of said shell and cap.

3. A rope supported device having in combination, a shell adapted to centrally receive a rope, a member co-operating therewith said shell and member each having interior means adapted to clamp the strands of said rope and interfitting means also adapted to clamp said strands. 95

4. A rope supported device having in combination, a shell adapted centrally to receive a rope, a member co-operating therewith, said shell and member each having interior means adapted to clamp the strands of said rope and having spaced interfitting means disposed outwardly of said first mentioned means also adapted to clamp said strands. 100 105

5. A rope supported device having in combination, a shell adapted centrally to receive a rope and having an interior flange and openings therethrough for respectively receiving the strands of said rope, a cap co-operating with said shell adapted to clamp said strands against said flange and having means interfitting with said shell also clamping said strands, said flange having means for receiving and preventing rotation of a bolt and said cap having a central aperture and a bolt passing through said flange and aperture for drawing and holding said shell and cap together. 110 115 120

6. A rope supported carrier comprising a cylindrical shell into which a rope centrally passes, means for clamping said rope in said shell, said shell having a flat top surface about said rope and housing sleeve loosely surrounding said rope and shell having an internal shoulder seated and supported on said top surface and adapted to swivel thereon. 125

7. A rope supported and clamping means 130

having in combination, a shell having openings to receive the separated strands of a rope and spaced outer and inner means against which said strands are clamped, a cap co-operating with said shell to clamp said strands against both means, and means for drawing and holding said shell and cap together.

8. A rope supporting and clamping device having in combination, a substantially cylindrical shell into which the rope centrally passes having a flange with circumferentially spaced passages through which the strands of the rope are adapted to pass, said shell having circumferentially spaced slots through which said strands project radially below said flange, a cap fitting in said shell below said flange adapted to engage and clamp said strands against said flange and having projections adapted to enter said slots also clamping said strands and preventing relative rotative movement of said shell and cap, and means for drawing and holding said cap and shell together.
- 23 9. A rope supported device having in com-

bination, a member adapted centrally to receive a rope, a member co-operating therewith through which the rope also centrally passes, said members having means adapted to clamp the separated strands of said rope and also having additional interfitting means adapted to clamp said strands.

10. A rope supporting and clamping means having in combination, a shell having a cylindrical wall and a transverse web 35 therein, said web being spaced from said wall to form a plurality of spaced openings through which separated strands of a rope pass, said wall having notches formed therein through which said strands also pass and a member co-operating with said shell and adapted to be secured thereto for clamping said strands against said web and in said notches.

11. The structure set forth in claim 10 said member being disposed within said wall and having projections thereon fitting in said recesses and clamping said strands therein.

In testimony whereof I affix my signature.
SAMUEL L. HANSON.
